UNITED STATES PATENT OFFICE.

JOHN PERCY HART, OF BRIDGEPORT BOROUGH, PENNSYLVANIA.

HOTEL-REGISTER.

No. 817,851.

Specification of Letters Patent.

Patented April 17, 1906.

Application filed May 19, 1905. Serial No. 261,213.

To all whom it may concern:

Be it known that I, JOHN PERCY HART, a citizen of the United States, residing at Bridgeport borough, in the county of Fayette and State of Pennsylvania, have made certain new and useful Improvements in Hotel-Registers, of which the following is a specification.

In my improved hotel-register the leaves whereon the names and addresses of guests are inscribed are loose and detachable in place of being bound together as in the ordinary register, a special means for fastening being employed, whereby they may be quickly separated one from the other, as required. The part or carrier upon which the leaves are laid and secured is adapted to revolve upon a base having an antifriction-bearing which is adjustable vertically, and between the leaf-carrier and base is interposed an antifriction-bearing, means being provided for holding the revolving part central, so that there is no lateral oscillation. The revolving part or carrier for the register proper is provided with foldable top sections which when closed serve as a cover and protector for the register, and the same are provided with spaces for reception of advertisements and ornamental panels.

30 The details of construction, arrangement, and combination of parts are as hereinafter described, reference being had to the accompanying drawings, (three sheets,) in which—

Figure 1 is a plan view of my improved register with the cover or protector closed. Fig. 2 is a transverse section on the line 2 2 of Fig. 1. Fig. 3 is an end view of one of the folding top sections or covers, its members being shown separated at an angle as when the cover is being opened or closed. Fig. 4 is mainly a plan view of the register, the folding top sections or covers being open and a portion being broken away to show the skeleton base-plate. Fig. 5 is a perspective view illustrating the end flanges with which the folding sections or covers are provided. Fig. 6 is a plan view of the base or base-plate inverted. Fig. 7 is a section on the line 7 7 of Fig. 1. Fig. 8 is a sectional perspective 50 of the angular flange forming a rigid attachment of the revolving part upon which the register proper is supported and secured when in use. Fig. 9 is a perspective view illustrating the means for fastening the register leaves to the revolving carrier and support. Fig. 10 is a perspective view of the nut or ad-

justable central bearing for the revolving carrier.

Referring in the first instance particularly to Figs. 2, 6, and 7, A indicates a circular skeleton base-plate, B the revolving frame or carrier upon which the register proper is laid and secured, and C the folding top sections or covers for the register proper. The base-plate A (see especially Fig. 6) is constructed in skeleton form and provided with a flange a. It is further provided centrally with a circular opening a', in which a circular nut D (see Figs. 2, 7, and 10) is screwed. The top of the nut D is beveled or inclined outward and downward to serve as a bearing for anti-friction-balls d, that travel in a circular runway b, provided in the revolving carrier B. This runway is lined with hard metal to prevent wear. A right-angular flange E (see Figs. 2, 7, and 8) is attached to the under side and rim of the revolving carrier B by means of screws, the horizontal member e of said flange projecting beneath the flange a of the base-plate A and being raised above the level of the bottom of the base A, so that when the carrier revolves it does not come in contact with the part upon which the base A rests. Between the two parallel portions a and e of the parts A E is interposed a series of antifriction-balls e', which are arranged to travel in a trough or groove formed in the under side of the flange a. This groove is preferably lined with compressed-fiber paper to prevent noise or rattling in the operation of the register. The balls e' travel on a rubber strip e'', which is provided with a groove in its upper side and held in a groove in the flange of the part E. It will be seen that the bevel of the nut D tends to hold the circle of antifriction-balls d concentric with itself, or, in other words, prevent lateral movement or shucking of the revolving carrier B. The rim or edge of the annular flange a of part A is, however, close to the vertical portion of the angular flange E, which is a further safeguard against lateral movement of the carrier B. The weight of the carrier B and its attachments is borne mainly by the balls d, traveling on the bevel-nut D, the balls e' serving chiefly as a means for balancing or steadyng the carrier B, so as to prevent vertical oscillation. If desired, the balls e' may be dispensed with altogether and the flanges a and b allowed to run in easy contact. It is apparent that by the arrangement of the nut D in the central threaded opening of the base

plate A a fine adjustment may be made by rotating the nut to secure the proper bearing of the balls d and e' in the first instance and also to take up wear of the same which may occur in the course of the use of the register.

By inspection of Figs. 1 and 4 it will be seen that the revolving register-carrier B is rectangular and from Figs. 2, 4, and 7 that it has a rectangular depression which serves to receive the leaves F, constituting the register proper. Between these leaves and the skeleton base-plate A is interposed a pasteboard or other plate G. (See Fig. 4.) As shown at the left hand, Fig. 4, a detachable fastening is provided for the leaves, the same consisting of a strip H, of spring metal, the same having three slots h h' , one being central and the other two near the ends thereof. There are also three pins or headed studs h^2 h^3 , which are set in the bed of the carrier B and are spaced apart corresponding to the slots h h' . The central slot h' is made large enough to receive the head of the stud h^3 , and the other two slots h are keyhole shape. The spring-strip H has a normal curvature, the ends curving upward. Thus to apply the strip to the studs h^2 h^3 for securing the leaves F the central portion requires to be bent upward in order to allow the studs h^2 to pass through the larger portions of the keyhole-slots h . When the strip straightens out, the studs h^2 enter the reduced portions of the slots h , and thus hold the strip in place. It has therefore greater pressure or bearing at points between the central stud h^3 and the outer stud h^2 . In order to detach it, it is bent upward in its central portion or at points intermediate of the two sets of studs, whereupon the slots h are freed from the studs h^2 . It will be understood that the several leaves F are provided with openings in the left-hand edge corresponding to the studs h^2 and h^3 , so that they may be slipped on the same before the strip is applied. The leaves or sheets F will in practice be ruled on both sides, so that when one side is filled with the names and addresses of guests of the hotel the leaves may be reversed. When both sides of a leaf have been filled with names, a new one is substituted, and so on until the carrier is filled, when they are all removed and placed on file for future reference. As shown in Fig. 4, a narrow strip of metal I is arranged at the top of the leaves F and serves for inscription of the words "Time," "Room," "Check," "Name," "Residence," &c., and the leaves are ruled vertically corresponding to the divisions or spaces thus indicated. The lower edge of the carrier B is provided with a narrow ledge b' , (see Fig. 4,) which serves, primarily, as a support for the hand of a guest when writing his name at or near the lower edge of a leaf F. It may serve also for name and address of the manufacturer.

As shown in Fig. 7, the ledge b' is provided

on its under side with a groove b^2 , which may in practice serve to receive lead if required to counterbalance the revolving carrier B. To the upper side of the carrier is attached a bracket or shelf J, (see Figs. 1, 4, and 7,) which is inclined at an angle of about forty-five degrees and supports a name-plate bearing the names of the hotel and the proprietor, &c. Such name-plate may preferably be placed under a glass which forms an ornamental appendage of the bracket or shelf J. To the ends of the latter are attached rings j , which may serve to support holders for matches and toothpicks. The lateral or side edges of the carrier are formed with upwardly-projecting flanges b^3 , (see Fig. 2,) and to these the outer sections or divisions of the folding covers C are hinged, as shown. The two sections are indicated by letters c c' , and they are hinged together in a longitudinal direction. They are constructed in skeleton form, thus adapted for reception of advertisements and ornamental panels—that is to say, the outer section c is provided with a mirror c^7 and the section c' is divided into three spaces, each of which receives a glass c^4 , which will cover and protect an advertising-sheet c^5 . Beneath the mirror c^7 and also beneath the glass c^4 and the advertising-sheet c^5 I arrange a sheet-metal plate c^6 , which is secured by screws to the under side of the sections c c' . A strip of pasteboard is interposed between the mirror c^7 and the sheet-metal projecting plate c^6 .

When the sections C are folded inward in the position indicated in Figs. 1 and 2, they completely cover and effectively protect the register proper from access of dust or dirt, and for a further protection they are adapted to fit down closely at the ends, being for this purpose provided with flanges c^3 c^8 . (See Fig. 5.) Adjacent to the flange c^8 is formed a groove c^9 , which receives the flange c^3 when the sections C are folded outward, as in Fig. 4; but when the sections C are folded inward, as in Figs. 1 and 2, the said flanges fit down closely upon the top and bottom edges of the rectangular body of the revolving carrier B, and thus serve as dust-excluders, as well as supports for the folding sections. It will be seen that when the said sections are folded outward the part c' lies upon and is supported by the part c , the latter being in turn supported by its hinge and the narrow ledge or lateral strip b^4 . (See Figs. 2 and 3.) Fig. 3 shows the part or section c thus supported and the other part c' slightly raised therefrom, as in the operation of either folding or opening.

By the construction, arrangement, and combination of parts before described I provide a highly-ornamental apparatus which is adapted to protect the register proper and allow the same to be readily detached when required and is also adapted to revolve easily and noiselessly, while provision is made for

taking up wear, so that the adjustment is kept practically perfect.

Having thus described my invention, what I claim as new, and desire to secure by Letters Patent, is—

1. The combination with an annular base-plate having a flanged rim and central opening, of a rotary carrier for the register proper, the same being mounted on the base and having a pendent angular flange projecting under the base-flange, a nut arranged in the central opening of the base and having a beveled rim, and antifriction-balls interposed between the said flanges and the carrier and nut, substantially as described.
2. The combination with an annular base-plate having a flanged rim, and a central opening, of a rotary carrier for the register proper, which is mounted on the base-plate, and provided with a pendent angular flange projecting under the base-flange, and a nut arranged in the central opening of the base-plate and having a beveled top, and antifriction-balls arranged between the nut and the carrier, substantially as described.
3. The combination with an annular base-plate having a central opening, of a rotatable register-carrier mounted thereon and having a pendent flange embracing the edge of the base-plate, and a nut arranged in the central opening of the base-plate and adapted for vertical adjustment for supporting the carrier in the manner described.
4. The combination with an annular base-plate, and a register-carrier adapted to revolve thereon, of a central bearing provided on said base-plate and a series of antifriction-balls, with compressed-fiber-paper bearings, interposed between the parts, substantially as described.
5. The combination with the annular base-plate, having a flanged rim, of the register-carrier mounted rotatably thereon and having an annular pendent and detachable flange whose horizontal portion projects beneath the flange of the rim, and a series of antifriction-balls, provided with compressed-fiber-paper bearings, interposed between the respective parts, substantially as described.
6. The combination with the base-plate, and the register-carrier mounted rotatably thereon, of a cover and protector for the register proper, the same comprising hinged sections which are attached to the side edges of the carrier and adapted to be folded inward and outward in the manner described.

7. The combination with a base-plate, and the register-carrier arranged rotatably thereon, and provided with upwardly-extending side flanges, of a cover and protector for the register proper, which comprises foldable sections hinged to the said flanges and provided with end flanges which when the cover is folded inward rest upon the top and bottom edges of the carrier, substantially as described.

8. The combination with a base-plate and a register-carrier mounted thereon and having upwardly and laterally extended flanges, of a cover formed of foldable sections which are hinged together and hinged to the said flanges on the inner side thereof, so that when folded outward they rest upon and are supported by the lateral projections of said flanges, substantially as described.

9. The combination with a base and a rotatable register-carrier mounted thereon, and having upwardly-extending side flanges, of the cover and protector for the register proper comprising hinged and foldable sections whose ends are provided with flanges adapted to lap past each other when the sections are folded outward, and which rest upon the top and bottom edges of the carrier when the sections are folded inward, substantially as described.

10. The combination with a base-plate and a register-carrier, of a cover and protector for the register proper, comprising sections which are hinged and adapted to fold inward and outward, the same being constructed in skeleton form with openings adapted to receive advertising media and ornamental attachments, glass panels inserted in the openings in the cover, advertising media arranged beneath the same, and plates secured beneath the said media for holding the parts in place, substantially as described.

11. The combination with a base-plate, of a register-carrier mounted thereon and provided with a series of headed studs arranged at one side, and a detachable fastening for leaves applied to said studs, the same comprising a curved spring-metal strip having slots adapted to receive the said studs, whereby the strip is locked with the same, substantially as described.
